UNITED STATES PATENT OFFICE.

GEORGE W. RAWSON, OF CAMBRIDGE, MASSACHUSETTS.

HOISTING-BUCKET.

SPECIFICATION forming part of Letters Patent No. 394,297, dated December 11, 1888.

Application filed June 20, 1888. Serial No. 277,620. (No model.)

To all whom it may concern:

Be it known that I, GEORGE W. RAWSON, a citizen of the United States, residing at Cambridge, in the county of Middlesex and State of Massachusetts, have invented certain new and useful Improvements in Hoisting-Buckets; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 is a longitudinal and vertical section, Fig. 2 a vertical and transverse section, Fig. 3 a side elevation, and Fig. 4 an end elevation, of a bucket provided with my improvement, with the jaws open, or in the position in which they are to be when lowered into contact with the material or substance with which said bucket is to be filled. Fig. 5 is a side elevation of the said bucket with its jaws closed.

25 The nature of my invention is defined in the claims hereinafter presented.

In the drawings, A denotes the bucket, it having two jaws, B B, each provided with eyes a a, which receive and turn on a pivotal shaft, C, arranged with said eyes, as shown, and also answer as weights to facilitate the opening of the bucket.

30 The shaft C is provided at its middle, between its ends, with a block, D, having pivoted within it sheaves b, as represented, and arranged on each side of the block D, and between it and the eyes a a, are sleeves E E, which serve the purpose of collars to keep the block D from undue endwise motion on 35 said shaft.

40 Pivoted to each side of each of the jaws B B, and near to the upper corners thereof, and also to ears f f of the head-block F, are rods G, there being four of said rods in number, as shown. The head-block F has pivoted within it sheaves c, and on each of two sides is provided with an eye, d, said eyes d being arranged in a horizontal plane at right angles to that of the ears f f. A rope, H, secured at one 45 end in one of the eyes d, passes down under the sheaves b and over the sheaves c successively, and then is carried up through the

other eye d of the head-block, and is secured to a drum supported above it in the usual manner. Another line, I, is connected to an eye, e, fastened to the head-block, and is carried upward and fixed to another drum arranged on the same shaft with the first-mentioned drum, said drums having arranged between them, and keyed to the shaft on which they are supported and revolve, a gear-wheel provided in each side with a conical chamber to receive a correspondingly-shaped cone formed on the adjacent end of each drum. Said drums are moved into or out of connection with the said gear by means of an independent lever connected to each. The gear-wheel referred to receives its motion from a pinion fixed on a driving-shaft in the usual manner.

50 The bucket hereinbefore described is intended particularly for use in unloading vessels laden with coal, and is to be lowered with the jaws in the position shown in Fig. 1 into the hold of the vessel and dropped into contact with the coal. The drum to which the line H is secured is next to be set in motion by clutching it to the gear hereinbefore referred to. Said line will then be wound on the drum. The block D will now approach 55 the block F, and the jaws will be forced into the coal with a downward force that will constantly increase as they close toward each other, and the bucket will be filled therewith. As soon as the jaws close against each other 60 the drum of the line I is to be clutched to the said clutching-gear, and both lines will now assist in raising the bucket to the necessary height. The bucket is next swung over the bin-car or chute which is to receive the coal, 65 and the drum of the line H unclutched from the clutching-gear, which being done, the jaws will open and the contents of the bucket will instantly be discharged therefrom. Next, 70 after swinging the bucket to the desired position, unclutch the drum of the line I from its clutching-gear, and the bucket will descend into the hold of the vessel for another load.

75 I am aware of the hoisting-bucket shown and described in United States Patent No. 362,528, dated May 10, 1887, and therefore make no claim to anything shown therein. The devices for operating my bucket being above the pivotal shaft do not come into con-

tact with or rub against the material with which the bucket is being filled, and consequently less power is required to operate or close the jaws than is requisite in a bucket having a drum provided with a wheel of larger diameter arranged on the pivotal shaft, which drum and wheel when lowered into contact with the material with which the bucket is to be filled are forced by the weight of the bucket into said material and revolved in contact therewith. The operative chains of said wheel and drum also, by being drawn through said material, rub against it during the closing of the jaws, and thus produce an amount of friction that demands a considerable increase of power to overcome.

Having described my invention, what I claim is—

1. In a hoisting-bucket, the combination of the pivoted jaws, the rods G, pivoted to the buckets and to the head-block, the said head-block provided with sheaves arranged therewith, as shown, the block D, supported on the pivotal shaft of the buckets and provided with sheaves which, during the closing of the jaws by the operative line or chain, stand wholly above said shaft, for the purpose described, the single operative line or chain H, secured to the head-block, passing under the sheaves of the block D and over those of the head-block and upward through the said head-block, as shown, and the hoisting-chain I, connected to the head-block, all substantially as shown and set forth.

2. The head-block F, substantially as de-

scribed, it being provided with the ears d, l and f, projecting from its body, and having pivoted within said body sheaves e, and provided with an eye, e, as shown, in combination with the pivoted jaws B, shaft C, block D, rods G, pivoted to the jaws and to the head-block, and the lines H and I, secured to the head-block, the former being arranged with the blocks D and F, as shown, to operate the jaws of the bucket, all being for use essentially as set forth and represented.

3. The block D, as connected to the pivotal shaft of the buckets and provided with rollers or sheaves arranged to stand wholly above said pivotal shaft while they (the said sheaves) are being revolved and drawn upward toward the head-block by the operative line or chain to close the jaws of the bucket, in combination with the jaws, the pivotal shaft thereof, the rods pivoted to the jaws and to the head-block, the said head-block provided with sheaves and eyes, as described, the hoisting line or chain connected to said head-block, and the operative line or chain H, for closing the jaws, it being attached at one end to one of the blocks and carried over and under the sheaves of the blocks, and finally upward through the head-block, all substantially as shown and set forth.

In testimony whereof I affix my signature in presence of two witnesses.

GEO. W. RAWSON.

S. N. PIPER,

C. F. DANIELS.

Corrections in Letters Patent No. 394,297.

It is hereby certified that in Letters Patent No. 394,297, granted December 11, 1888, upon the application of George W. Rawson, of Cambridge, Massachusetts, for an improvement in "Hoisting Buckets," errors appear in the printed specification requiring correction, as follows: In line 30, page 1, a period should be substituted for the comma after the word "shown," and the remainder of the paragraph stricken out; in line 40, same page, the period after the word "shaft" should be stricken out and the words, *and also answer as weights to facilitate the opening of the bucket*, should be inserted, and the said Letters Patent should be read with these corrections therein that the same may conform to the record of the case in the Patent Office.

Signed, countersigned, and sealed this 8th day of January, A. D. 1889.

[SEAL.]

D. L. HAWKINS,
Assistant Secretary of the Interior.
